AUTOMATIC DAM

Henry D. Bentrup, Deerfield, Kans.

Application July 9, 1953, Serial No. 366,953

13 Claims. (Cl. 61—29)

The present invention relates to an automatic dam. It has to do particularly with an automatic dam having a flexible dam curtain which may be released at a predetermined time and which will be played out by the downstream movement of the water in an irrigation ditch to dam up the water in said ditch.

Various types of automatic dams have been available heretofore but most of them have been of rather complicated and thus costly construction, including many parts or units and thus making them extremely clumsy and cumbersome to handle and transport from place to place. The present invention is related to and an improvement upon that of my co-pending application Serial No. 186,091.

One of the objects of the present invention is to provide a new and improved automatic dam of the foregoing character which is of relatively few operating parts and being positive in its action of entering the irrigation ditch quickly and effectively to dam up the water in said ditch.

Another object of the present invention is to provide a new and improved portable automatic dam having clock controlled release mechanism for releasing the flexible dam curtain at a predetermined or set time.

A further object of the present invention is to provide flexible dam curtain supporting and releasing means which is easily transportable from place to place and which is of compact nature whereby the entire assembly may be stored in a relatively small space.

The foregoing and other objects and advantages of the present invention will appear from the following description and appended claims when considered in connection with the accompanying drawings forming a part of this specification wherein like reference characters designate corresponding parts in the several views.

In said drawings:

Fig. 1 is a top plan view of a portion or section of an irrigation ditch and connecting lateral or side ditch, showing the application of the automatic dam of the present invention thereto, the parts being indicated in their out-of-use positions and also in their stream-damming positions.

Fig. 2 is a longitudinal vertical section, partly in elevation, of the structure shown in Fig. 1, being taken substantially along the line 2—2 of Fig. 1, looking in the direction of the arrows.

Fig. 3 is an enlarged scale fragmentary elevational view taken substantially along the line 3—3 of Fig. 1, looking in the direction of the arrows; and

Fig. 4 is an enlarged scale perspective view, partly broken away, being taken generally along the line 4—4 of Fig. 1, looking in the direction of the arrows.

Before explaining in detail the present invention it is to be understood that the invention is not limited in its application to the details of construction and arrangement of parts illustrated in the accompanying drawings, since the invention is capable of other embodiments and of being practiced or carried out in various ways. It is to be understood also that the phraseology or terminology employed herein is for the purpose of description and not

2

of limitation, and it is not intended to limit the invention claimed herein beyond the requirements of the prior art.

Referring now to the drawings, the main irrigation ditch to which the automatic dam assembly of the present invention is applied is shown at 10, lateral or side ditches which are connected with the main ditch being shown at 11 in Fig. 1.

The flexible dam curtain employed with the assembly is shown as a whole at 12. This curtain may be of any desired length suitable for the purpose, the length and the width of the curtain depending upon the depth and width of the irrigation ditch to be dammed up.

The lead or free end 13 (see Fig. 3) of the curtain carries a series of weights, such as those shown at 14 in Figs. 1, 2 and 3. These weights may be attached to the free or lead end of the curtain in any suitable manner, as by means of short ropes or cable 15 which preferably pass through eyelets 16 fastened in the curtain material adjacent the free edge 13 thereof.

The curtain 12 is wound or wrapped around a ditch-straddling pole-like member or roll 16, the end thereof adjacent the member 16 being securely fastened to it. The pole-like member or roll 16 has a reduced diameter or portion 17 at one end which provides, in effect, a spool to receive a rope or cable 18, one end of which is securely fastened to the spool or portion 17, with the remaining length of the rope or cable 18 being wound around the spool, as shown in Figs. 1 and 3. The other end of the long rope or cable 18 is fastened to a member or part of the curtain release mechanism and will be described below.

It is desirable to stake the so-called free edge 13 of the curtain to the earth at the opposite sides of the irrigation ditch 10 in the vicinity of the lateral or side ditches 11. For this purpose, the side corners of the curtain 12 are provided with eyelets 19 through which are passed and secured lengths of rope or cable 20 having at their outer free ends stakes 21. Thus, it is possible to stake or removably connect the weighted end 13 of the flexible dam curtain to the banks of the ditch. The inactive or out-of-use position of the dam curtain is shown in full lines in Figs. 1, 2 and 3, with the curtain 12 being wrapped or rolled onto the ditch-spanning and supporting member 16. The in-use or operative position of the curtain 12 and the ditch-spanning member 16 is shown in broken lines in Figs. 1 and 2.

I shall now describe the automatic release and dam curtain operating mechanism of the invention. This mechanism is shown in Figs. 1, 2 and 4 and comprises a frame shown as a whole at 22. The frame includes spaced ground-engaging base portions 23 and 24 having upright portions 25 and 26 and a longitudinally extending elevated portion or section 27. The portions 23, 24, 25, 26 and 27 are the supporting portions of the frame assembly 22 and provide means for supporting and permitting the upright swinging movement of a releasable arm 28 to which one end of the rope or cable 18 is attached. The arm 28 has a preferably horizontally disposed opposite end portion 29 being provided with an eye 30 at its end to receive the rope or cable 18. The opposite end of the arm 28 has a right angularly disposed portion 31 having an eye 32 formed in its end. In its inoperative position, the end portion 31 extends downwardly toward the earth but when the arm 28 is released, this member extends upwardly, the latter position not being shown in the drawings. The arm 28 carries a projecting finger 28a which is disposed adjacent the juncture of the arm 28 and the opposite end 29, see particularly Fig. 4, for a purpose to be described. A coiled tension spring 33, see Figs. 2 and 4, has one end fastened in the eye 32 and the opposite end to a bracket 25a carried by the upright portion 25 of the frame.

The arm 28 is pivotally mounted adjacent one end upon a pivot pin or member 34 which extends through the longitudinal portion or member 27 of the frame, being held in spaced relation and substantially parallel to the frame member 27 by a spacing sleeve or member 35, see Fig. 4. The ground-engaging or base member 24 of the frame carries a sleeve 36 attached to a stake 37 which permits the member 24 to be staked to the earth to hold the frame against movement during the releasing action of the dam curtain 12.

The frame member 27 is provided with a plate or platform 38 which carries a clock or timing mechanism, such as an ordinary alarm clock, shown as a whole at 39. As best seen in Figs. 2 and 4, the alarm clock has the usual time and alarm winding handles 40 and 41, respectively. The handle 41 is provided with an aperture or opening 41a. An arm-engaging link or member, shown as a whole at 42 has its upper angularly disposed end portion 43 extending through the opening 41a, see particularly Fig. 4, and has its lower substantially right angular end portion 44 extending downwardly from the upright portion of the member 42 underlying the longitudinal arm 28 and being disposed between and in contact with the underside of arm 28 and the upper surface of the projecting portion or member 28a, as clearly shown in Fig. 4.

With the parts in the position in which they are shown in Figs. 1, 2 and 4, the tension spring 33 maintains the arm 28 under tension so as to cause the projection 28a to engage the trigger end portion 44. When the alarm mechanism of clock 39 is released, turning of the alarm winding handle 41 will move the trigger 42 out of engagement with the projection or finger 28a, thus allowing the spring 38 to swing arm 28 about its pivot 34 in an upright direction toward the left as viewed in Fig. 1, or toward the right as viewed in Figs. 2 and 4, thus pulling on the cable or rope 18. This in turn unwinds the rope from spool 17, turning the ditch-spanning member 16 to unwind the flexible curtain 12 to allow the weights 14 to carry the curtain 12 downwardly in the ditch, whereupon the water will cause the necessary submersion of the curtain 12 to dam up the stream to approximately the water level indicated at 50 in Fig. 2. During this unwinding and stream-damming action of the curtain 12, the stakes 21 and the curtain-attaching ropes 20 maintain the so-called free end 13 of the curtain in more or less its original position, thus permitting the movement of the ditch-spanning member 16 from its full line position in Fig. 2 to its broken line position in that view and the unwinding or unrolling of the curtain 12.

After sufficient water has been dammed up to serve the required irrigating purposes, the mechanism may be re-set by swinging the arm 28 from its broken line position to its full line position and moving the trigger 42 into its position of Fig. 4 to hold the swinging arm 28 in its set or out-of-use position. The flexible dam curtain 12 is, of course, rewound or rolled onto its supporting roll 16.

If it is desired to move the automatic dam assembly to another position along the same ditch 10 or to a different ditch, it is merely necessary to pull the stakes 21 and 37 from the earth and carry the curtain-supporting means and the curtain-releasing means to a new location. The parts are relatively lightweight and being easy to carry, one person can easily transport, if desirable, to complete automatic dams in accordance with the present invention.

It is to be understood, of course, that various types of time controlled means may be substituted for the clock mechanism 39 and various types of trigger or arm-holding and releasing means may be substituted for the trigger 42 shown in the drawings merely by way of example.

While I have shown the use of weights 14 attached to the curtain and portion 13 for lowering the curtain into the stream when the mechanism is released, a suitable pocket could be formed in that end of the curtain and filled with some liquid which is heavier than water for

the purpose of causing the curtain to lower itself into the water when released.

From the foregoing it will be seen that I have provided an automatic dam curtain which requires merely a single ditch and stream-spanning member, such as member 16, to support the curtain either in its out-of-use position or in its stream-damming position.

I claim:

1. In an automatic dam for use with an irrigation ditch, a flexible dam curtain, a support for said dam curtain capable of straddling the irrigation ditch, one end of the curtain being attached to said support and the other end thereof being free, weight means carried by the free end of said curtain, means for removably staking said free and weighted end of the curtain to the earth at opposite sides of the ditch, and means disposed at one side of the ditch and connected to said support for moving the support to unroll the curtain into the ditch to dam up the water therein.
2. An automatic dam according to claim 1, wherein said means includes a spring-tensioned releasable arm.
3. An automatic dam according to claim 1, wherein said means includes a frame, a swingable arm carried by the frame, a tension spring interconnecting one end of said arm and a portion of the frame, and a time-controlled releasable latch member for releasing the swingable arm at a predetermined time.
4. An automatic dam according to claim 1, wherein the support for the dam curtain has a fixed spool portion at an end therein, and wherein said means includes a rope attached at one end to the spool portion and wound around the same.
5. An automatic dam according to claim 1, wherein the support is a bar having spool portions at its opposite ends, and wherein said means includes a rope attached to one of the spool portions and wound around the same.
6. An automatic dam according to claim 1, wherein the dam curtain support is a bar having a spool portion at an end thereof, wherein said means includes a rope attached at one end to the spool portion and wound around the same, and wherein said means also includes time-controlled release means connected to the other end of the rope.
7. An automatic dam for use with an irrigation ditch, a flexible dam curtain, a support for said dam curtain capable of straddling the irrigation ditch, one end of the curtain being attached to said support and the other end thereof being free, weight means carried by the free end of said curtain, means for removably staking said free and weighted end of the curtain to the earth at opposite sides of the ditch, and time-controlled mechanism disposed at one side of the ditch and connected to one end portion of the dam curtain support for moving the support to unroll the curtain into the ditch and dam up the water therein at a predetermined time.
8. An automatic dam for use with an irrigation ditch, comprising a flexible dam curtain, a support for the dam curtain capable of straddling an irrigation ditch and upon which the curtain is rolled up when not in use, one end of the curtain being attached to the support with the other end of the curtain being free of the support, weights on the last-named end of the curtain, and automatically releasable means connected to the dam curtain support for moving the support and curtain bodily to unroll the curtain and lower it into the irrigation ditch to dam up the water therein.
9. An automatic dam according to claim 8, wherein the automatically releasable means is spring-powered.
10. An automatic dam according to claim 8, wherein the automatically releasable means is releasably staked down at a side of the irrigation ditch.
11. Means for releasing a rolled up canvas dam curtain into an irrigation ditch at a predetermined time for damming up the water in said ditch, comprising a frame

adapted to be placed at one side of the irrigation ditch, said frame comprising spaced upright portions having ground-engaging end portions and a longitudinally extending portion between and connecting the upright portions, a platform mounted upon the frame, a swingable arm pivotally connected to the frame and extending in substantial parallelism to the longitudinal portion of the frame when the device is in inoperative position, a tension spring interconnecting a portion of the frame and one end of said swingable arm, the opposite end of said arm having an offset portion providing means for attaching a rope to be connected to the rolled up dam curtain, means for maintaining the spring-tensioned arm in inoperative position when desired, clock mechanism mounted on said platform, and means forming a part of said clock mechanism to move the maintaining means out of engagement with the swingable arm at a predetermined time to release said arm and effect the unrolling of the dam curtain.

12. Time-controlled means for shifting the position of a portable dam curtain-supporting member and unrolling a flexible dam curtain therefrom, comprising a one-piece frame having spaced upright portions terminating at their lower ends in ground-engaging portions, interconnecting substantially horizontal longitudinally extending portion between the upright portions, means for removably pinning the frame to the ground, a swingable arm pivotally connected to the frame adjacent an

end thereof, a tension spring interconnecting one end portion of said swingable arm and a portion of said frame whereby to maintain the arm under tension when in inoperative position, means connecting the opposite end of the swingable arm to the dam curtain-supporting member, and movable trigger means associated with the time-controlled means and the swingable arm to release the arm and shift the position of the curtain-supporting member and curtain at a predetermined time.

10 13. Automatic means for releasing a portable dam curtain at a predetermined time, comprising a frame, a swingable arm member mounted on said frame, a tension spring connecting a portion of said arm to a portion of said frame to maintain the arm under tension when the device is in inoperative position, means interconnecting the swingable arm and the dam curtain to be released, manually settable clock mechanism carried by said frame, and trigger means interconnecting the clock mechanism and arm to release the latter at a predetermined time.
